UNITED STATES PATENT OFFICE.

WILLIAM LEICHTFUSS, OF NEW YORK, N. Y.

WINDOW-PANE FASTENER.

1,426,204.

Specification of Letters Patent. Patented Aug. 15, 1922.

Application filed April 12, 1921. Serial No. 460,761.

To all whom it may concern:

Be it known that I, WILLIAM LEICHTFUSS, a citizen of the United States, and a resident of the city of New York, Elmhurst, in the 5 borough of Queens and county of Queens and State of New York, have invented a new and Improved Window-Pane Fastener, of which the following is a full, clear, and exact description.

10 This invention relates to window pane fasteners for securing and retaining window panes in the sashes in lieu of putty.

The device is especially designed for use in connection with hot house sashes where 15 the employment of putty for this purpose has been found extremely undesirable in that the heat tends to crack and dry out the putty after a short length of time.

The invention seeks for one of its principal objects to provide a simple and inexpensive pane fastening means which is easy to apply or remove and which when arranged in place will function to efficiently retain the pane in the sash irrespective of 25 extreme temperatures to which the same may be subjected.

Another object of the invention resides in the provision of a fastening or retaining means which is held in place by headed fastening elements such as nails, screws or the like and which is constructed in such a manner as to shield the heads of the fastening elements to prevent catching of the clothing thereon or tearing of the hands.

35 With the above recited and other objects in view the invention resides in the novel construction and arrangement of parts set forth in the following specification, pointed out in the appended claim and disclosed in 40 the accompanying drawings, in which;

Figure 1 is a sectional perspective view illustrating the use and application of the fastening means.

Figure 2 is an enlarged detail sectional 45 view of the same.

Referring to the drawings by characters of reference, 10 designates the sash rails provided with the usual rabbeted portions 12 which receive the edges of the window 50 pane 13. In lieu of putty or other retaining means, the pane fastener constituting the invention is employed and the same comprises a thin flat strip of metal 14 which is preferably provided with a centrally arranged longitudinally extending depression 15 which provides in the outer face thereof a groove 16. The depressed portion of the strip is

formed with a plurality of spaced apertures 17 for the reception of the fastening elements 18 provided with heads 19. In use 60 and application of the fastener the strip is arranged obliquely in the corner formed at the juncture of the pane 13 with the sash rail, with the opposite edges of said strip respectively engaging said rail and the pane. 65 The fastening elements 18 are passed through the apertures 17 and the extremities thereof are anchored in the sash approximately at the point of contact of the edge of the pane therewith. When the fastening 70 elements have been driven home the heads 19 are designed to lie within the grooves 16 formed by the depression 15 whereby to protect the same. The depressed portion 15 in addition to forming the grooves 16 constitutes a strengthening rib throughout the 75 length of the strip. The strip as stated is preferably formed of metal or any other suitable material which is comparatively rigid. It will thus be seen that a simple, inexpensive pane fastening is provided which is readily applicable to a sash or removable therefrom, and one which will resist the extreme differences in temperature to which it may be subjected.

80 While there has been illustrated and described a single and preferred embodiment of the invention, no limitation is necessarily made to the precise structural detail as it is understood that variations and modifications 85 which fall within the scope of the appended claim may be resorted to when found expedient.

I claim:

90 A device for fastening a window pane in a rabbeted sash, comprising a flat metallic strip of material having a longitudinally extending centrally arranged V-shaped depression forming a groove of gradually decreasing widths at the transverse center of 95 said strip, said strip adapted for oblique arrangement within the angle formed at the juncture of the pane with the sash to dispose the opposite edges thereof respectively 100 in engagement with the sash and pane, said strip adapted to have fastening elements driven through the V-shaped depressed portion thereof and anchored in the sash with the heads thereof disposed within the groove 105 defined by the depressed portion of the strip 110 whereby said heads will be gripped by the V-shaped groove and retained in a countersunk position.

WILLIAM LEICHTFUSS.
